HERBERT A. WALLACE, OF EDGEWOOD BOROUGH, PENNSYLVANIA, ASSIGNOR TO THE UNION SWITCH & SIGNAL COMPANY, OF SWISSEVALE, PENNSYLVANIA, A CORPORATION OF PENNSYLVANIA.

APPARATUS FOR TRANSMITTING CODE-IMPULSE COMBINATIONS.

Application filed May 8, 1925, Serial No. 28,798. Renewed April 25, 1928.

My invention relates to apparatus for transmitting code impulse combinations.

Apparatus embodying my invention is particularly adapted for, though in no way limited to, supplying the trackway of a railway with code impulse combinations which may be used to control trackway signals or train carried governing mechanism, or both.

I will describe two forms of apparatus embodying my invention, and will then point out the novel features thereof in claims.

In the accompanying drawings, Fig. 1 is a view, largely diagrammatic, showing one form of apparatus embodying my invention. Fig. 2 is a fragmental view showing, in top plan, the retarding magnet E of Fig. 1. Fig. 3 is a view showing another form of apparatus also embodying my invention. Fig. 4 is a top plan view of the dash pot 20 of Fig. 3. Fig. 5 is a sectional view along line V—V of Fig. 4.

Similar reference characters refer to similar parts in each of the several views.

Referring first to Fig. 1, the reference characters 1 and 1^a designate the track rails of a stretch of railway track. These track rails are divided, by means of insulated joints 2, into a plurality of track sections, of which only one section, A—B, is shown in the drawing.

This track section is at times supplied with code impulse combinations by a transmitter designated in general by the reference character W. In the form here shown this transmitter comprises a shaft 6 supported in suitable journals not shown in the drawing. Attached to this shaft is a vane 5 of electro-conducting material, by the weight of which the shaft is biased to a position in which the vane abuts against a fixed stop 61. A flexible cord 7 is wrapped around shaft 6 and carries a plunger 8. This plunger is provided with a winding 9 so disposed that when the winding is energized plunger 7 is drawn downwardly, thereby rotating shaft 6 in a counter clockwise direction as seen in Fig. 1, and raising vane 5 against the force of gravity. The motion of vane 5 is at times retarded by a damping magnet E (see Fig. 2), comprising a magnetic core 14 provided with a winding 15. The damping magnet is

so disposed that magnetic flux created in the core 14 traverses vane 5, creating eddy currents in the vane which oppose motion of the vane. A contact member 16 is operated by a dog 90 controlled by vane 5 so that when the vane is in its lower position contact 16—16^a is closed. As the vane moves upwardly this contact remains closed until the vane reaches the upper limit of its stroke, at which time dog 90 engages finger 16 to open contact 16—16^a and to close contact 16—16^b. As the disk returns to its lower position contact 16—16^a remains closed until the vane reaches its lower position when dog 90 again engages finger 16 so that contact 16—16^a opens and contact 16—16^b again closes.

The vane 5 also operates four other contacts 20, 19, 18 and 17 in such manner that when the vane is in its lower position contact 20 is closed and contacts 19, 18 and 17 are all open. When the disk commences to move upwardly contact 20 opens. After the vane has moved through about one quarter of its stroke, contact 19 closes; after the vane has moved through one half of its stroke, contact 18 closes; and after the vane has moved through about three fourths of its stroke, contact 17 closes. When the vane is at the top of its stroke, therefore, contacts 17, 18 and 19 are all closed and contact 20 is open. As the vane returns to its lower position, contacts 17, 18 and 19 are successively opened as the vane completes about one quarter, one half and three quarters of its stroke, respectively, and contact 20 is therefore closed when the vane reaches its initial position.

A pawl 10 is pivoted to vane 5 at point 11. This pawl is constantly urged by a spring 12 into engagement with the teeth of a ratchet wheel 13, the parts being so arranged that the ratchet wheel is advanced one tooth in a counter clockwise direction for each upward stroke of the vane. I have here illustrated the ratchet wheel with six teeth so that six cycles of vane 5, each comprising an upward stroke and a downward stroke are required to cause one complete rotation of wheel 13, but this particular proportion of parts is not essential to my in-

vention. Three cams 21, 23 and 25 are operatively connected with wheel 13 and rotate in unison therewith. The cam 21 is provided with three swells 21^a spaced about 5 its periphery and co-operating with a contact 22 so that the contact is closed when engaged by one of the swells 21^a. The parts are so disposed that contact 22 is closed by the upward stroke of each alternate cycle 10 of vane 5 and this contact then remains closed till the next successive upward stroke of the vane. Cam 23 is provided with swells 23^a similar to those provided on cam 21, and this cam operates a contact 24 in the 15 same manner as explained in connection with contact 22, but the cams are staggered on their axis so that during the alternate cycles when contact 22 is closed, contact 24 is open and vice versa. Cam 25 is provided 20 with two diametrically disposed swells 25^a co-operating with two contacts 26 and 27. It will be plain from the drawing that the upward stroke of each third cycle of vane 5 will close contact 27, that the upward 25 stroke of the next succeeding cycle will open contact 27 and close contact 26, and that the upward stroke of the next cycle of vane 5 will then open contact 26.

The time required for each cycle of the 30 vane is controlled by the damping magnet E which is, in turn, controlled by contacts 19, 18 and 17 operated directly by the vane, by contacts 22, 24, 26 and 27 operated by the ratchet wheel 13, and by a selector G. 35 This selector comprises a pivoted lever 28 and a plurality of fixed contacts co-operating therewith. The lever 28 may be operated by any suitable means forming no part of my present disclosure and omitted from 40 the drawing for the sake of simplicity. In actual practice the lever would usually be controlled by traffic conditions in advance.

The immediate source of code impulse combinations for section A—B is a transformer T, the primary 3 of which is constantly supplied with alternating current from the terminals C and D of a suitable source of energy not shown in the drawing. Secondary 4 of transformer T is connected, through contact 20 operated by vane 5, across the rails adjacent the right hand end of section A—B. Alternating current is therefore supplied to the rails only when contact 20 is closed.

55 A track relay R is connected across the rails adjacent the left hand end of section A—B and is responsive to current supplied to the rails of the section by transformer T.

As shown in the drawing all parts of the 60 apparatus are in their normal positions, that is, vane 5 of transmitter W rests against stop 61, and contacts 16—16^b and 20 are closed, but contacts 19, 18 and 17 are open. Contacts 22 and 26 are closed, and contacts 65 24 and 27 are open. All contacts of selector

G are also open. Under these conditions alternating current is continuously supplied to the rails of section A—B, and relay R is therefore energized.

In explaining the operation of the apparatus I will first assume that contact 28—29 of selector G is closed, and that relay R becomes de-energized, as by the entrance of a train into section A—B. Current then flows from terminal C of a source of energy not 70 shown in the drawing, through back contact 40 of relay R, wire 41, contact 16—16^b, wire 9^a, and winding 9 to terminal D of the same 75 source. Winding 9 is therefore energized, drawing plunger 8 downwardly and rotating shaft 6 in a counter clockwise direction. Vane 5 is lifted by this operation, but the damping magnet E has substantially no retarding effect upon this motion of the vane 80 because no current flows through winding 15, all circuits for this winding being open at contact 16—16^a. When vane 5 has completed 85 its stroke dog 90 operates contact 16 interrupting the circuit just traced and de-energizing winding 9. Vane 5 therefore 90 commences to return to its lower position under the influence of gravity. The closing of contact 16—16^a however completes a circuit for the damping magnet E, from terminal C, 95 through back contact 40 of relay R, wire 41, contact 16—16^a, wire 42, lever 28 and contact 29 of selector G, wires 43 and 44, contact 17 operated by vane 5, wire 45, and winding 15 of damping magnet E to terminal D of the same source. The damping 100 magnet therefore retards the motion of vane 5 in returning to its lower position as long as contact 17 remains closed. After the vane 105 has moved downward about one quarter of its stroke, however, this contact opens and the vane thereafter moves without retardation. The time required for the cycle 110 of the vane under these conditions is therefore comparatively short, the vane being retarded through only a comparatively small portion of its downward motion. When the vane returns to its lower position, contact 16 again rotates to energize winding 9 and the cycle just described is repeated. Each 115 time the vane reaches its lower position contact 20 is closed, and an impulse of alternating current is then delivered to the rails of the section by transformer T. It will therefore be plain that when relay R is de-energized, and when contact 28—29 of selector G 120 is closed, section A—B is supplied with a code impulse combination made up of successive impulses each comprising a plurality of alternations and each impulse separated from the preceding impulse by a comparatively short time interval.

If contact 28—30 of selector G is closed the operating circuit for winding 9 is not affected, but at the end of the upward or drive stroke of vane 5, when contact 16 op- 125

erates, a circuit is closed for the damping magnet from terminal C, through back contact 40 of relay R, wire 41, contact 16—16^a operated by vane 5, wire 42, contact 28—30 5 of selector G, wire 46, contact 18, wires 48 and 45, and winding 15 of magnet E to terminal D. It will be clear that under these conditions, each downward stroke of vane 5 is retarded by the magnet E as long as contact 18 is closed, that is, through about one half of such stroke. Each cycle of the vane therefore consumes a greater length of time than when contact 28—29 of selector G is closed and the rails of section A—B are 15 therefore supplied with code impulse combinations made up of successive impulses each impulse separated from the preceding impulse by a time interval of what I shall call medium length to distinguish from the 20 short time intervals of the code impulse combinations supplied by the transmitter when contact 28—29 of selector G is closed.

Similarly, when contact 28—31 of selector G is closed, the damping circuit is from 25 terminal C, through back contact 40 of relay R, wire 41, contact 16—16^a, wire 42, contact 28—31 of selector G, wire 49, contact 19, wires 50, 48 and 45, and winding 15 of magnet E to terminal D. With this circuit 30 closed each downward stroke of vane 5 is retarded through three quarters of this stroke and the cycles each require a comparatively long time. Section A—B is therefore supplied with a code impulse combination comprising impulses separated by comparatively 35 long time intervals.

I will now assume that lever 28 of selector G is moved into engagement with contact 32. In this position the lever also engages 40 contact 36. The damping circuit may then be traced from terminal C, as before, to lever 28, and from this lever the circuit divides into two branches, one passing through contact 32, wires 43 and 44, contact 17, and wire 45 to winding 15 of magnet E, and the other through contact 36, wires 51 and 52, contact 22 operated by cam 21, wires 53 and 46, contact 18, and wires 48 and 45 to winding 15 of magnet E. Assuming that the 45 parts of the apparatus are in the positions illustrated in the drawing, the upward stroke of the first cycle of vane 5 opens contact 22, so that when the vane returns to its lower position, the branch for the damping 50 circuit through contact 18 is open but the branch through contact 17 is closed and the downward stroke therefore requires only a short time interval. The upward stroke of the next cycle of vane 5 again closes contact 55 22, and as the vane returns to its initial position the second time damping is continued through one half the downward stroke. Under these conditions, then, section A—B is supplied with a code impulse combination 60 in the form of successive impulses separated

by time intervals of which alternate intervals are of short duration and the remaining intervals are of medium duration.

If lever 28 of selector G is moved to engage contacts 33 and 37, a damping circuit 70 having two other branches is provided for supplying energy to magnet E. This circuit passes as before from terminal C to lever 28, thence dividing, one branch passing through contact 33, wires 43 and 44, contact 17 and wire 45 to winding 15 of magnet E; and the other branch passing through contact 37, wire 54, contact 24 operated by cam 23, wires 55 and 49, contact 19, and wires 50, 48 and 45 to winding 15 of magnet E. 80 With this adjustment of the selector it will be plain from the foregoing that the code impulse combinations supplied to the trackway comprises successive impulses separated by time intervals of which alternate time 85 intervals are of short duration, and the remaining time intervals are of long duration.

If lever 28 of selector G is moved into engagement with contacts 34 and 38, one branch of the circuit for winding 15 of magnet E contains contact 22 and contact 18, and the other branch contains contact 24 and contact 19. These circuits will be plain from the drawing without tracing them in detail. With the selector in this position, the time 90 intervals between successive impulses in the code impulse combinations supplied to the trackway are alternately of medium and of 95 long duration.

When lever 28 of selector G is moved to engage contacts 35 and 39, the magnet E is energized over a circuit having one branch including contact 28—35 of the selector and contact 17, as will be plain without further description. A second branch passes from lever 28 through contact 39, wire 56, contact 26, wires 57 and 49, contact 19, and wires 50, 48 and 45 to winding 15 of magnet E; and a third branch passes through contact 39, wire 56, contact 27, wires 58 and 46, contact 18, and wires 48 and 45 to winding 15 of magnet E. I will first assume that wheel 13 is in the position illustrated in the drawing so that contact 26 is closed and contact 27 is open. On the next upward stroke of vane 5, contact 26 will be opened. Contact 27 will remain open, and on the subsequent downward stroke, vane 5 being retarded by magnet E only so long as contact 17 is closed completes the first cycle in a comparatively 100 short time. The upward stroke of the next cycle closes contact 27, and the downward stroke of the vane during this cycle is therefore retarded till contact 18 opens. Similarly, the next upward stroke closes contact 105 26, and the following downward stroke of the vane is then retarded till contact 19 opens. It will be plain, therefore, that the time intervals between successive impulses 110 of the code impulse combination supplied 115

to the trackway are successively of short, medium and long duration.

The code impulse combinations supplied to the trackway by the transmitter may be used to control any desired traffic governing apparatus, not shown in the drawing, in any suitable manner.

I will assume that a train occupies section A—B, so that relay R is de-energized 10 and the apparatus is supplying the trackway with code impulse combinations according to one of the codes described, depending upon the position of selector G. When this train moves out of the section, the impulses 15 supplied to the track rails energize relay R. Back contact 40 of relay R therefore opens. All circuits for transmitter W are therefore open, and contact 20 remains closed. Alternating current, is, then, continuously 20 supplied to the rails and relay R remains energized. It follows that the current supplied to the rails by transformer T is broken up into code impulse combinations only when the relay R is de-energized, as by the 25 presence of a train in section A—B.

Referring now to Fig. 3, the reference character P designates a magnet device comprising a flat bottom plate 62^a upon which is supported a series of other plates 62^c, 30 62^b and 62^a, each of which latter plates is provided at its outer edge with a dependent skirt or flange, by means of which the plate is supported by the plate immediately below it, and in spaced relation therewith. 35 Each of the plates 62 is of magnetizable material, such as soft iron. Between plates 62^a and 62^b is an annular solenoid magnet 64, a similar winding 65 is located between plates 62^b and 62^c, and a third winding 66 is 40 placed between plates 62^c and 62^a.

Normally suspended from each plate 62 is a plunger of magnetizable material designated by the reference character 63 with the same exponent as that applied to the associated plate. The plunger 63^a is attached to plate 62^a and constitutes a fixed stop. The parts are so proportioned that with all the windings 64, 65 and 66 de-energized, the plungers 63 are supported in spaced relation 45 by the associated plates 62. When winding 66 is energized, plunger 63^d is lifted into engagement with plunger 63^c; when windings 65 and 66 are both energized, plungers 63^c and 63^d are both lifted till plunger 63^c 50 engages 63^b; and when windings 64, 65 and 66 are all energized, plungers 63^b, 63^c and 63^d are all lifted till plunger 63^b engages the fixed stop 63^a. It will thus be seen that, 55 the amount of upward motion of plunger 63^d depends upon how many of windings 64, 65 and 66 are energized.

A dash pot K (see also Figs. 4 and 5) 60 controls the motion of plunger 63^d. This dash pot comprises a cup 73 containing a fluid such as mercury 72. Rigidly attached

to the lower side of plunger 63^d is a disk 70 which enters the cup 73 with a small annular clearance and dips in the mercury 72. The disk 70 is provided with segmental openings which are at times closed by a 70 segmental disk 71 loosely attached to plunger 63^d beneath disk 70. During motion of plunger 63^d upwardly the inertia of the mercury forces the disk 71 away from disk 70 and uncovers the segmental openings so that only a small force retards this motion. When the plunger returns to its lower position, however, the disks are forced together, and the displaced mercury must flow through the annular clearance space between the edges of the disks and the cup 73. The dash pot K therefore retards downward motion of plunger 63^d, but not upward motion of the plunger. 75

A plate M is attached to plunger 63^d, which plate is provided with three notches 67, 68, 69, for operating the three contacts 17, 18 and 19, respectively. When plunger 63^d is in its lower position contacts 17, 18, and 19 are all closed. If winding 66 is 80 energized plate M is raised to open contact 17, but contacts 18 and 19 remain closed; if windings 66 and 65 are both energized, plate M is raised far enough to open contacts 17 and 18 but contact 19 remains closed; and if windings 64, 65 and 66 are all energized plate M is lifted to its highest position and contacts 17, 18 and 19 are all opened. When the plate M returns to its lower position contacts 19, 18 and 17 are all closed 85 at the end of the downward stroke.

A pawl 74 pivotally mounted on plate M operates ratchet wheel 13 so that the ratchet is advanced one tooth for each upward motion of plate M. Contacts 22, 24, 26 and 105 27 are controlled by cams operated by ratchet wheel 13 in the same manner as in Fig. 1.

The contact 20 for controlling the supply of current from transformer T to the rails 110 of the section is operated by plate M so that the contact is closed only when plate M is in its lower position.

By means of selector G, energy is supplied to any selected ones of the windings 115 64, 65 or 66. For example, when contact 28—29 of selector G is closed and back contact 40 of relay R is closed, a circuit may be traced from terminal C, through back contact 40 of relay R, wire 41, contact 28—29 of selector G, wires 43 and 44, contact 17, wire 75, and winding 66 to terminal D. Plunger 63^d is therefore lifted into engagement with plunger 63^c, opening contact 20. This motion is substantially unretarded by 120 the dash pot K. When this upward motion is completed contact 17 is opened, thereby de-energizing winding 66. Plunger 63^d then returns, under the influence of gravity, 125 to its lower position, being retarded in this 130

- motion by the dash pot K. When the plate M reaches its lower position contact 20 is again closed, and contact 17 is also closed, again energizing the winding 66. With the 5 relay R de-energized therefore, with contact 28-29 of selector G closed, the transmitter closes contact 20 at short intervals corresponding to the similar intervals of the apparatus shown in Fig. 1.
- 10 If contact 28-30 of selector G is closed, windings 65 and 66 are both energized over contact 18, the circuit being plain from the drawing, and in this case, the upward motion of plunger 63^d being greater, the return 15 to its lower position requires a medium length interval. The long time intervals between impulses is obtained by closing contact 28-31 of selector G, thereby energizing all three of the windings 64, 65 and 66 over 20 contact 19 for the upward motion of plunger 63^d. The plunger then requires a comparatively long interval of time to return to its lower position.

The various arrangements of code impulse 25 combinations are obtained by moving the lever 28 of selector G to the corresponding positions, and the operation of the apparatus will be understood from the explanation of the apparatus shown in Fig. 1 without tracing 30 the operation in detail.

Although I have herein shown and described only two forms of code impulse transmitting apparatus embodying my invention, it is understood that various 35 changes and modifications may be made therein within the scope of the appended claims without departing from the spirit and scope of my invention.

- Having thus described my invention, what 40 I claim is:
1. Code impulse transmitting apparatus comprising a pair of conductors, a member arranged to move through cycles of motion, a contact controlled by said member for varying the time required for each such cycle, and means controlled by said member for supplying code impulse combinations to said conductors.
  2. Code impulse transmitting apparatus 45 comprising a pair of conductors, a member biased to an initial position, means for moving said member away from said initial position, a contact responsive to the position of said member, means controlled by said contact for retarding the return of said member to said initial position, and means controlled by said member for supplying code impulse combinations to said conductors.
  3. Code impulse transmitting apparatus 50 comprising a pair of conductors, a member biased to an initial position, means for moving said member away from said initial position, means for retarding the return motion of said member to its initial position, 55 means for rendering said retarding means

effective through a variable portion of such return motion, and means controlled by said member for supplying code impulse combinations to said conductors.

4. Code impulse transmitting apparatus 70 comprising a pair of conductors, a member biased to an initial position, means for moving said member away from said initial position, a magnet for retarding the return motion of said member to its initial position, a 75 contact responsive to the position of said member, a circuit for said magnet including said contact, and means controlled by said member for supplying code impulse combinations to said conductors.

5. Code impulse transmitting apparatus 80 comprising a pair of conductors, a member biased to an initial position, means for moving said member away from said initial position, a magnet for retarding the return 85 motion of said member to its initial position, a plurality of contacts successively operated by said member, means for including a selected one of said contacts in circuit with said magnet, and means controlled by said member for supplying code impulse combinations to said conductors.

6. Code impulse transmitting apparatus 90 comprising a pair of conductors, a member biased to an initial position, means for moving said member away from said initial position, a magnet for retarding the return motion of said member to its initial position, a 95 plurality of contacts arranged to be closed when said member is moved away from its initial position and to be successively opened as the member returns to its initial position, means for including a selected one of said contacts in circuit with said magnet, and means controlled by said member for supplying code impulse combinations to said conductors.

7. Code impulse transmitting apparatus 100 comprising a pair of conductors, a member biased to an initial position, means for moving said member away from said initial position, a magnet for retarding the return motion of said member to its initial position, a 105 plurality of contacts arranged to be closed when said member is moved away from its initial position and to be successively opened as the member returns to its initial position, means for including a selected one of said contacts in circuit with said magnet, a source of alternating current, and another contact 110 controlled by said member for at times connecting said source with said conductors.

8. In combination, a stretch of railway 115 track, a track relay for said stretch, a member biased to an initial position, a first contact responsive to the position of said member, means controlled by said relay and by said first contact for repeatedly moving said member away from said initial position, means for retarding the motion of said mem- 120

ber by an amount which varies as the member returns to its initial position, and a second contact controlled by said member for supplying code impulse combinations to said 5 stretch.

9. In combination, a pair of conductors, a member biased to an initial position, means for repeatedly moving said member away from such initial position, a magnet for retarding the motion of said member in returning to its initial position, a plurality of contacts arranged to be closed when the member is moved away from such initial position but to be successively opened as the 10 member returns, other means controlled by said member for including different ones of said contacts in series with said magnet during successive strokes of said member, and still another contact responsive to the position 15 of said member for supplying code impulse combinations to said conductors.

10. A transmitter for code impulse combinations comprising a member arranged to move through a cycle of motion, mechanism 20 for operating said member, a contact mechanism advanced one step for each cycle of said member, and means controlled by said

mechanism for varying the time required for each cycle of said member.

11. Code impulse transmitting apparatus 30 comprising a pair of conductors, a member biased to an initial position, means for moving said member away from said initial position, a contact responsive to the position of said member, means controlled by said contact for varying the time required for each complete cycle of said member, and means controlled by said member for supplying code impulse combinations to said conductors. 35

12. Code impulse transmitting apparatus comprising a pair of conductors, a member biased to an initial position, means for moving said member away from said initial position, means for retarding the motion of said member, means for rendering said retarding means effective through a variable portion of the cycle of said member, and means controlled by said member for supplying code impulse combinations to said conductors. 45

50 In testimony whereof I affix my signature.

HERBERT A. WALLACE.
